UNITED STATES PATENT OFFICE

162,942

POWDER CAN HOLDER OR SIMILAR ARTICLE

George W. Emmert, Chicago, Ill., assignor to Federal Premium Service Corporation, Chicago, Ill., a corporation of Illinois

Application November 28, 1947, Serial No. 142,861

Term of patent 3½ years

(Cl. D58—17)

To all whom it may concern:

Be it known that I, George W. Emmert, a citizen of the United States and a resident of Chicago, in the county of Cook and State of Illinois, have invented a new, original, and ornamental Design for a Powder Can Holder or Similar Article, of which the following is a specification, reference being had to the accompanying drawing, forming part thereof, in which:

Figure 1 is a side view of a powder can holder, showing my new design;

Figure 2 is a top plan view of the same;

Figure 3 is a bottom plan view of the same; and
Figure 4 is a top perspective view.

I claim:

The ornamental design for a powder can holder or similar article, as shown.

GEORGE W. EMMERT.
